DECALCOMANIA PAPER AND TRANSFER

Ferdinand W. Humphner, Oak Park, Ill., assignor
to Mid-States Gummed Paper Co., Chicago,
Ill., a corporation of Illinois

Application May 4, 1935, Serial No. 19,875

3 Claims. (Cl. 41—33)

This invention relates to decalcomania paper and transfers and more particularly to a decalcomania product having a continuous film body adapted to be broken up into segments upon the moistening of the paper base.

An object of the invention is to provide a decalcomania paper or transfer which is so constructed as to permit ready separation of a main or continuous body into individual transfers when the paper base is moistened. A further object is to provide a decalcomania transfer having a lacquer body thereon, means being provided for breaking up the lacquer body into separate pre-formed segments when the lacquer body is freed from the base. A further object is to provide a lacquer body which may be equipped with prints or designs, said lacquer body being provided with weakened lines along which the body breaks when the lacquer is freed from the paper base. Other specific objects and advantages will appear as the specification proceeds.

The invention is illustrated, in preferred embodiments, by the accompanying drawings, in which—

25 Figure 1 is a broken plan view of a decalcomania product embodying my invention; Fig. 2, a broken sectional view, the section being taken as indicated in line 2 of Fig. 1; Fig. 3, a broken sectional view illustrating a modified form of the invention; Fig. 4, a perspective view of a tablet or book containing a decalcomania product illustrating another form of my invention; Fig. 5, a broken sectional view, the section being taken as indicated at line 5 of Fig. 4; and Fig. 6, a plan view of a modified form of the invention.

Referring to the construction shown in Figs. 1 and 2, I prefer to employ a large paper sheet of suitable composition which may, if desired, be coated with a starch layer. Upon the paper or 40 starch may be placed a suitable gum or water-soluble adhesive. The gum is preferably fractured to prevent non-curling. Upon the gum layer is placed a body or layer of lacquer which extends completely over the strip to provide a 45 surface upon which prints may be placed.

I have found that the continuous lacquer body, as described above, can be employed while at the same time, providing segmental areas upon which special designs, such as stamp designs, may be placed, the areas supporting the designs being readily detachable, by forming across the top of the lacquer body a series of intersecting lines produced by the application of suitable solvents. The line areas may be formed by applying the 55 solvents to metal edges and the metal edges then

pressed against the top of the lacquer body. A satisfactory method of applying the solvents is to employ a printing plate having raised intersecting lines and then printing the lacquer top with the plate after it has been connected with 5 solvents.

Any suitable solvents may be employed. With the solvents, I incorporate a plasticizer which serves to keep the weakened line areas in a soft or plastic condition for a long time. One solvent 10 and plasticizer combination which I have found satisfactory is as follows:

	Percent
Ethyl acetate	20
Dibutyl phthalate	20
Monoethyl ether of ethylene glycol	60

To the above, I add non-drying oils of suitable viscosity to form a printing base as required to meet the particular mechanical equipment employed. Various vegetable oils, such as castor oil, 20 may be employed. The above solution has been found satisfactory as a solvent solution when used with a lacquer formed in accordance with the formula set out in my Patent 1,965,289, which 25 issued July 3, 1934. It will be understood that for different types of lacquers, different types of solvents will be found suitable and such solvents will readily occur to anyone skilled in this art.

In the operation or use of the decalcomania product shown in Figs. 1 and 2, the paper base is moistened together with the gum layer and the lacquer body, which will, of course, be provided with suitable prints or designs, is then broken into separate small bodies of regular shape 30 by means of the weakened lines produced by solvents. Ordinarily, the user will slip off the small segments near one end of the paper and then proceed to slip off additional squares or segments 35 as they are needed, leaving the remainder of the segments intact upon the paper base.

While I have shown in the foregoing paragraphs a preferred method or means for forming weakened line areas in the lacquer body, it 40 will be understood that many other methods 45 may be employed.

In the construction shown in Fig. 3, I take a sheet of paper having starch, if desired, and gum thereon, and then emboss or press the gum-equipped paper into the shape shown in Fig. 3, the face of the paper being thus provided with a series of pockets or depressions which may be round, rectangular, square, or of any other desired shape. Next I flow a body of lacquer over 50 55

the embossed paper to form a top even surface upon which prints may be placed. It will be observed that the lacquer in one of the pockets forms a substantial body adapted to carry a print while the lacquer extending over the raised wall between the depressions is very thin. Thus the thin sections of lacquer provide weakened lines along which the lacquer body will break. If desired, the thin areas of lacquer may be narrowed to form a narrow dividing line between the lacquer pockets or blocks.

In the operation or use of the product shown in Fig. 3, when the paper and gum is moistened, the embossed character of the paper tends to disappear to a substantial extent and the lacquer bodies may be readily removed from the base, the lacquer bodies breaking away from each other along the weakened lacquer lines.

In Figs. 4 and 5, I have shown another form of decalcomania product in which the lacquer body is weakened along intersecting lines by cutting through the lacquer body and also partly through the paper at spaced intervals. Sheets of such decalcomania paper are illustrated in Fig. 4 as being secured together in tablet or book form.

Cutting disks, presses or other suitable mechanical means may be employed to cut through the lacquer body to form the intersecting lines illustrated in Fig. 4. These intersecting lines which extend through the lacquer body are indicated by the numeral 10. Below the cuts 10, I form at spaced intervals deeper cuts 11 which extend through the gum and starch layers and partially into the paper body.

With the construction shown in Fig. 5, the individual squares or rectangles formed by the lines 10 may be removed upon the weakening of the gum layer by moistening. However, if desired, the user may tear off a portion of the paper itself containing the superposed gum and lacquer layers, the cuts 11 in the paper base permitting the paper to be torn evenly along the cut lines 11. The small paper strip may then be moistened and the transfer slipped off and onto the desired surface.

While, in the foregoing illustrations, I have shown square or rectangular areas suitable for receiving designs or imprints, it will be understood that such areas may be circular or of any other desired shape. Also, it will be understood that the foregoing examples are merely illustrative of various ways of forming the weakened areas, and that other means might readily be employed by men skilled in the art to accomplish such results without departing from the spirit of my invention.

In the modification shown in Fig. 6, a large sheet is constructed as illustrated in Figs. 1 and 2, except that the weakened areas delineate a figure in the shape of a horseshoe rather than intersecting lines which formed squares for revenue stamps and other designs. The horseshoe construction shown in Fig. 6 is illustrative of other designs which may be formed by the weakened areas. When the transfer is separated from the base, it may be attached as a body to a surface and then the portion of the transfer about

and inside the horseshoe may be peeled away to leave only the horseshoe attached to the surface. In other words, the use of weakened lines permits any type of figure to be attached to a surface and portions of the body then removed to leave 5 the figure in sharp outline on the surface.

While I have described a specific form of paper and lacquer combination, it will be understood that any suitable base and any suitable print-carrying body secured to said base by a releasable 10 bond may be employed.

The foregoing detailed description has been given for clearness of understanding only, and no unnecessary limitations should be understood therefrom, but the appended claims should be 15 construed as broadly as permissible, in view of the prior art.

I claim:

1. Decalcomania paper comprising: a paper base, a water-soluble adhesive thereon, a lacquer 20 body over said adhesive, a solvent for said lacquer body contacting certain spaced areas of said body to form weakened areas therein.

2. Decalcomania paper comprising: a paper base, a water-soluble adhesive thereon, a lacquer 25 layer over said adhesive, and a solvent and plasticizer contacting said body along certain areas to form separable areas of predetermined shape.

3. Decalcomania paper comprising: a paper base, a water-soluble adhesive thereon, a lacquer 30 body over said adhesive, and solvents for said lacquer printed upon the lacquer body to form weakened lines therein.

4. Decalcomania paper comprising: a paper base, a gum layer thereon, a continuous lacquer 35 body on said gum layer, said lacquer body having weakened areas extending part way through the depth of the lacquer body whereby upon the freeing of said lacquer body from said paper base, said lacquer body may be broken into segments 40 of predetermined shape.

5. A decalcomania comprising: a paper base, a gum layer thereon, said base and gum having depressed areas therein, a lacquer body extending over said depressed areas, and prints on the surface of said lacquer over said depressed areas. 45

6. Decalcomania paper comprising: a paper base having depressions formed therein, gum over said base, and a lacquer body flowed over the body of said gum and providing a level surface 50 adapted to receive imprints, said lacquer body being relatively thick above said depressions and being relatively thin in the areas between said depressions.

7. Decalcomania paper comprising: a paper 55 base, a water-soluble adhesive thereon, a lacquer body over said adhesive, and a material contacting certain spaced areas of said lacquer body to maintain the lacquer in said areas in soft and weakened condition.

8. Decalcomania paper comprising: a base, a water-soluble adhesive, a continuous lacquer body extending over said adhesive, said body having weakened line areas extending part-way therethrough whereby said body may be broken into 65 segments of predetermined shape upon the softening of said adhesive layer.

FERDINAND W. HUMPHNER.
